UNITED STATES PATENT OFFICE.

HENRY J. PLANT, OF ROCHESTER, NEW YORK, ASSIGNOR TO DEFIANCE CHECK WRITER CORPORATION, OF ROCHESTER, NEW YORK, A CORPORATION OF NEW YORK.

PRINTING-MACHINE.

1,300,007.

Specification of Letters Patent.

Patented Apr. 8, 1919.

Application filed March 15, 1916. Serial No. 84,437.

To all whom it may concern:

Be it known that I, HENRY J. PLANT, a citizen of the United States, and resident of Rochester, in the county of Monroe and State of New York, have invented certain new and useful Improvements in Printing-Machines, of which the following is a specification.

The present invention relates to printing machines.

An object of this invention is to provide a construction by which the dials which indicate the positions of the printing members, are arranged in juxtaposition in order that by a single glance at the dials one may ascertain the lines at the printing point. Another object of this invention is to provide an improved transmission means between the several printing members and their indicating dials. A further object of the invention is to provide a means by which the printing members may be quickly operated to point out main divisions thereon. A still further object is to protect the checks arranged in sheets so that a printed line will not be blurred by contact with the machine. Still another object of the invention is to provide, in a sheet check writer, devices which will act to position individual checks.

To these and other ends, the invention consists in certain parts and combinations of parts all of which will be hereinafter described, the novel features being pointed out in the appended claims.

In the drawings:

Fig. 1 is a plan view of a machine embodying the present invention;

Fig. 2 is a section on the line *a—a*, Fig. 1;

Fig. 3 is a section on the line *b—b*, Fig. 1;

Fig. 4 is a bottom view of the machine with the bed plate removed;

Fig. 5 is an enlarged sectional view of the centering device;

Fig. 6 is a detail sectional view showing the construction and arrangement of the individual check gage; and

Figs. 7 and 8 are detail views of another embodiment of the centering means.

Referring more particularly to the drawings, 1 indicates a base or bed plate preferably having a sheet of glass 2 inserted in the upper face thereof and serving as a surface on which ink may be arranged for supplying ink to ink rollers. To this bed plate, a casing 3 may be hinged at 4 and carries a latch 5 at its swinging end for engagement

with the bed plate. The top of this casing may be closed by a work supporting plate 6 which is provided with a slot 7 through which the check is pressed to engage with the printing members or member within the 60 casing.

The printing members are preferably in the form of four wheels 8, 9, 10 and 11 arranged in two sets. The wheel 8, in this instance, has lines of type thereon in the 65 form of words from one to one hundred; the wheel 9 has lines of type thereon in the form of numerals indicating fractional amounts of a dollar from one cent to ninety-nine cents, each fractional amount being followed 70 by the word "dollars"; the wheel 10 has lines of numerals thereon corresponding to the words on the wheel 8; and the wheel 11 has lines of numerals thereon corresponding to the matter on the wheel 9, so that the wheels 75 10 and 11 write in numerals on the check what has been written in words by the wheels 8 and 9.

It is desirable that the set of wheels 8 and 10 shall move together and the set of wheels 80 9 and 11. It is also desirable that each set of wheels shall have an indicator on the exterior of the case moving therewith and shall be operable from the exterior of the casing. In this embodiment of the invention, this 85 result is secured by a shaft 12 journaled at 13 in one side of the case 3 to project at one end through the case and having its opposite end journaled within a socket 14 formed in a shaft 15 which is axially alined with the 90 shaft 12 and turns in a sleeve 16 which is journaled at 17 in that wall of the casing 3 opposite the wall carrying the bearing 13. The wheel 8 turns loosely on the shaft 12, the wheel 9 is pinned to the shaft 12 at 18, the 95 wheel 10 is rigid with the shaft 15 and the wheel 11 turns on the shaft 15 and is rigid with the sleeve 16. The shaft 15 which projects both inside and outside of the casing 3 carries the wheel 10 within the casing and 100 carries the indicating wheel or member 18 on the exterior of the casing. The sleeve 16 also projects inside and outside of the casing 3 and carries the wheel 11 on the interior of the casing and the indicating wheel 19 105 on the exterior of the casing and in juxtaposition to the indicating wheel 18.

The indicating wheel 18 is turned by a grip member or wheel 20 which lies to one side of the wheel 18 and is connected with 110

the latter through lugs or projections 21 which are provided with numerals to indicate the main divisions of the indicator. From the indicating wheel 18, motion is transmitted by the shaft 15 directly to the printing wheel 10 and from the latter, by means of a gear wheel 22 concentric therewith and a pinion 23, motion is transmitted to a counter shaft 24 on which the pinion 23 is arranged. This shaft 24 also carries a pinion 25 which meshes with a gear wheel 26 carried by the type wheel 8 concentric with the latter so that the type wheel 8, the type wheel 10 and the indicator 18 are rotated simultaneously in the same direction when the hand wheel or operating member 20 is turned.

For operating the other set of type wheels and their dial 19, a hand wheel or operating member 27 is provided on that side of the machine opposite the hand wheel 20. This hand wheel 27 is pinned at 28 to the shaft 12 and causes the turning of the latter with the printing wheel 9. Secured to the printing wheel 9 and concentric therewith is a gear wheel 29 which meshes with a pinion 30 arranged on the counter shaft 31. This counter shaft 31 also carries a pinion 32 which meshes with a gear 33 that is secured to the printing wheel 11 concentric with the axis of rotation of the latter so that, when the hand wheel 27 is turned, the printing wheel 9 turns, transmitting motion to the printing wheel 11 by means of the interconnecting gears and pinions, and, at the same time, the dial member 19 is turned due to its connection with the printing wheel 11 by the sleeve 16.

It is desirable in machines of this type to have the printing lines center themselves automatically beneath the slot 7 and, to this end, each set of printing members is provided with centering means. The centering means for the set in which the printing wheel 8 is a member comprises a spring pressed plunger 34 coöperating with a notched centering wheel 35 which is secured to the printing wheel 8 and concentric with the latter.

50 The centering means for the other set of printing members embodies two centering devices 36 and 37, the former being adapted to coöperate with the centering wheel 38 and the latter coöperating with the centering wheel 39. Each of these centering devices is in the form of a plunger pressed toward its centering wheel by a spring 40 which surrounds the reduced portion of the plunger within the pocket of an attaching member 41. The tension of this spring may be regulated by a screw plug 42 through which the reduced portion of the stem of the plunger is guided, and this plug 42 has its outer end notched at 43 for the reception of the projections 44 or the enlarged

head of the plunger. If the plunger be pulled outwardly and turned slightly, the projections 44 will be carried out of the notches or recesses 43 and the plunger held out of coöperation with its centering wheel. 70 The purpose of this construction is to enable those printing wheels which print the fractional portion of a dollar to be centered either for one cent or for five cents. It is well known that many large employers of working people do not pay money to their help in coins less than a five cent piece, either paying more or less than the actual wages and adjusting this on the next pay day. It is for these employers that this attachment has been designed as it enables them to quickly ascertain the amount nearest to the actual wages of the employee without paying off in one cent pieces. At the same time, the machine may be adjusted to center 80 each line of this set of printing members. 85

The inking mechanism does not form any part of the present invention so a detailed description thereof will be unnecessary. A plurality of inking rolls 45 are yieldingly supported within a casing 46 which is to co-operate with the printing member. This casing is hinged at 47 to the rear wall of the casing 3 and is held in different adjusted positions by latches 48. In order that this 90 casing will not be required to sustain the weight of the machine when the casing 3 is swung on its pivot 4, the casing 3 is provided with lower feed or legs 48 projecting rearwardly therefrom below the ink roll casing 100 46 and upper feet or legs 49 projecting rearwardly therefrom above the ink roll casing 46. The feet or legs 49 are preferably curved in the manner shown so as to project slightly above the plan of the table 6 in order that 105 the sheet of checks may be directed thereon to be lifted slightly from the table 6 after the printing action so that the inked under surface of the check will not be blurred by contact with the table 6 or with the ink roll 110 casing 46. Before the work reaches the curved work supporting members 49 it is lifted slightly by the two fingers 86 which project upwardly and rearwardly from the table 6 in advance of the rear edge of the 115 table and in rear of the slot 7, these fingers being spaced apart so as to engage the work at opposite sides of the printed area and hold it elevated until it reaches the curved supports 49. 120

For impressing the checks upon the printing members, there may be employed a platen 50 which coöperates with all of the printing members and which preferably is secured to a head 51 from which extends a guide rod 52 that operates within a block 53. This block is preferably formed with an enlarged bore 54 in which is inclosed a helical spring 55 which surrounds the rod 52 and abuts at one end the bottom of the bore 54 and at its other 130

end the enlargement 56 on the stem 52. For coöperation with the enlarged end 56 of the stem 52 an operating lever 57 is provided pivoted at 58 to the head 53 in rear of the stem 52 and carrying an adjustable screw 59 engaging the enlarged portion 56.

The forward end of this lever or operating member 57 may be provided with a pocket 60 in which is received a cushion 61. The pocket 60 is formed by dividing the end of the operating member 57 to form a removable piece 62 which is secured by a screw 63 and provided with a tapered bore in which is fitted an inverted cup-shaped member of rubber or other yielding material with flaring walls. By removing the member 62, the cup-shaped member 61 may be removed, but it is otherwise held against removal by its flaring walls coöperating with the tapering 20 opening of the member 62.

The head 53 may be secured by screws 64 to a bridge piece 65 which is attached at its ends to opposite sides of the casing 3 so that a sheet of checks may be passed rearwardly 25 over the table 6 onto the curved guides 49. To guide the checks, guides 66 may be adjustably secured at 67 to the table 6 at opposite sides of the latter, and for holding the checks down on the table, spring-arms 68 30 are adjustably secured at 69 to the bridge 65 and extend forwardly and downwardly from the latter to bear against the table, these arms being connected near their outer ends by rods 70 which coöperate with the sheets of 35 checks to determine the printing position of the latter.

When the machine is to be used for printing on single checks, the spring arms 68 may be removed and the gages shown in Fig. 6 40 substituted therefor. These gages preferably have stop portions 71 vertically arranged and coöperating at their lower ends with the table 6 beneath the bridge piece 65. These vertical stop portions are each carried by one 45 end of a U-shaped member 72 one arm of which extends below the bridge 65 and the other arm of which extends above the bridge 65 and is provided with a slot 73 which permits the stop portion 71 to be adjusted toward and from the slot 7, the adjusting screw 50 69 operating in said slot portion 73.

In the operation of the invention, the hand wheels 20 and 27 are adjusted until the proper numbers on the dials 18 and 19 are 55 brought within the opening of the indicator loop 74. By this operation, the printing members 8, 9, 10 and 11 have been positioned so that lines of type are presented beneath the slot to print on a check in words and numbers 60 the amount of said check. Either a single check or a sheet of checks is then placed face downward on the table 6 and adjusted so that it lies in proper position over the slot 7, after which the operating handle 65 or member 57 is depressed to carry the platen

50 downwardly in order to force the check against the exposed type line.

Instead of the centering means shown in Fig. 5, the centering means shown in Figs. 7 and 8 may be employed. In this construction the two centering wheels 38 and 39 are provided as in the other embodiment, one with a notch for each line of type and the other with a notch for each five lines, so that the wheel will be centered only at lines 70 representing multiples of five. Instead of two plungers only one plunger 78 is employed in the form of a tube having a ball 75 79 in one end and pressed toward the centering wheel by a coil spring 81 which operates within the plunger 78 abutting the latter at one end, and a plug 82 at its other end, the plug being adjustable to vary the tension of the spring and being held in its adjusted position by a lock nut 83. The 80 plunger 78 is eccentrically carried by a rotary screw 77 which is adjustably mounted on a carrier 75 that is pivoted at 76 to the outside of the casing of the machine, the screw and plunger extending through an 85 opening in the casing to engage the wheels 38 and 39. A thumb screw 84 operates in a slot 85 and holds the carrier 75 in its adjusted position.

By this arrangement the single plunger or 90 centering device 78 may be made to engage either the centering wheel 38 or the centering wheel 39, and owing to the fact that the plunger is eccentrically mounted in a screw 77 it may be adjusted to shift the 95 centering position slightly so that proper engagement between the printing line and the platen may be obtained.

According to this invention, there has 100 been provided a structure in which two dials, controlled by separate operating members at different ends of the machine, are located in juxtaposition at one side of the machine, so that it is possible to determine immediately what adjustment of the printing 105 members has been effected. The mechanism for carrying out this result is of simple construction and not liable to get out of order. The inking casing is mounted at the rear of a hinged casing and is protected by feet 110 which support the hinge casing in open position. The printed check is protected against blurring by contact with the machine after the printing action. Centering means is provided which centers the set 115 printing wheel either for every line of type thereon, or for every fifth line of type thereon.

What I claim as my invention and desire 120 to secure by Letters Patent is:

1. In a check printing machine, the combination with two sets of type wheels arranged side by side along a common axis, one of said type wheels bearing figures, another and non-adjacent type wheel bearing 125

words expressing the corresponding figures on the first named wheel, a third wheel bearing figures, a fourth and non-adjacent wheel bearing corresponding figures, of a 5 shaft to which one of said type wheels is secured and on which another turns, a second shaft to which another of said type wheels is secured and on which another turns, and driving connections between each 10 rigidly secured type wheel on one shaft and the type wheel which turns on the other shaft.

2. In a check printing machine, the combination with two sets of type wheels arranged side by side along a common axis, 15 one of said type wheels bearing figures, another and non-adjacent type wheel bearing words expressing the corresponding figures on the first named type wheel, a third wheel 20 bearing figures, and a fourth and non-adjacent type wheel bearing corresponding figures, of a shaft to which one of said type wheels is rigidly secured and an adjacent type wheel turns thereon, a hand wheel on 25 said shaft, a second shaft to which another of said type wheels is rigidly secured and still another turns thereon, a hand wheel secured to the latter shaft, driving connections between the rigidly secured wheel on 30 each shaft and the loosely mounted wheel on the other shaft, two dials one secured to one of said shafts and the other mounted to turn loosely thereon, and driving connection between the loosely mounted dial and 35 the other shaft.

3. In a check printing machine, two printing wheels, a shaft for each wheel, a hand wheel on each shaft, two dials one rigidly secured to one shaft and the other mounted 40 to turn on the same shaft in proximity to the first named dial, and driving connection between said second named dial and the other shaft.

4. In a check printing machine, a casing, 45 two printing wheels mounted therein, two alined shafts one for each wheel, each of said shafts extending to the exterior of the casing, a hand wheel on the extended portion of each shaft, a dial on the extended 50 portion of one shaft to turn with the latter, and a dial mounted to turn loosely on said shaft in proximity to the first named dial and having driving connection with the other shaft.

5. In a check printing machine, two sets 55 of type wheels, a pair of alined shafts to each of which one of the type wheels of one of the sets is rigidly secured, and on each of which the other type wheel of the other 60 set is mounted to turn loosely, and driving connections between the loosely mounted type wheel on one shaft and the rigidly secured type wheel on the other shaft.

6. In a check printing machine, two sets 65 of type-wheels, a pair of alined shafts to

each of which one of the type wheels of one of the sets is rigidly secured, and on each of which the other type wheel of the other set is mounted to turn loosely, and driving connections between the loosely mounted type 70 wheel on each shaft and the rigidly secured type wheel on the other shaft, a dial rigidly secured to one of said shafts, a dial mounted to turn loosely on the same shaft, and a sleeve rigidly securing said dial to the type 75 wheel which turns loosely on the shaft.

7. In a check printing machine, a casing, two sets of type wheels arranged in the casing on a common axis, two alined shafts to each of which one of the type wheels of one 80 of the sets is rigidly secured, and on each of which the other type wheel of the other set is mounted to turn loosely, the shafts being extended from opposite sides of the casing, hand wheels secured to said extended 85 ends, and driving connections between the loosely mounted type wheel on each shaft and the rigidly secured type wheel on the other shaft.

8. In a check printing machine, a casing, 90 two sets of type wheels arranged in the casing on a common axis, two alined shafts to each of which one of the type wheels of one of the sets is rigidly secured, and on each of which the other type wheel of the other 95 set is mounted to turn loosely, the shafts being extended from opposite sides of the casing, hand wheels secured to said extended ends, and driving connections between the loosely mounted type wheel on each shaft 100 and the rigidly secured type wheel on the other shaft, a dial rigidly secured to one shaft on the exterior of the casing in proximity to the first named dial, and a sleeve connecting said last named dial with the 105 loosely mounted type wheel within the casing on the same shaft.

9. An operating lever for check printing machines or the like comprising a main portion, a removable portion having a tapered 110 opening closed at its bottom by the main portion, and an inverted cup-shaped impact cushion having flaring side walls co-operating with the tapered walls of the removable portion of the lever to be retained in said 115 opening and having its bottom resting upon the main portion.

10. In a check printing machine, a bed plate, a casing hinged at its rear to the bed plate, a printing wheel journaled in the casing, an ink-roll casing adjustably secured to said main casing at the rear of the latter and projecting therefrom, and legs projecting from the rear wall of the casing to support the latter when it is swung rearwardly so 120 that the weight of the casing and type wheel will not be placed upon the ink-roll casing.

11. In a check printing machine, a casing having a slotted top wall serving as a work support, a type wheel having its type adapt- 125 130

ed to be exposed through said slotted top wall, a platen for pressing the work into engagement with type on the type wheel, a support for the platen permitting the work 5 to be fed rearwardly over the top of the casing, and means acting on the under side of the work on opposite sides of the printed area after the printing to lift the work off the top to prevent blurring of the printed 10 matter.

12. In a check printing machine, a casing having a slotted top wall serving as a work support, a type wheel having its type adapted to be exposed through the slot, a platen 15 for pressing the work into engagement with type on the type wheel, a support for the platen permitting the work to be fed rearwardly over the top of the casing, two spaced fingers projecting from the top of the casing 20 between the slot and the rear edge of the top wall, and two spaced curved members projecting beyond the rear edge of the top wall and above the plane of the top surface to conduct the work to the rear of the casing 25 without contacting with the rear edge of the casing.

13. In a check printing machine, a casing having a slotted top wall serving as a work support, a type wheel having its type adapted to be exposed through said slotted top wall, a platen for pressing the work into engagement with type on the type wheel, a support for the platen permitting the work to be fed rearwardly over the top of the 30 casing, and spaced devices projecting rearwardly from the casing and adapted to support the work on opposite sides of the printed area after it has been printed to prevent blurring of the printed matter.

14. In a check printing machine, a casing having a slotted top wall serving as a work support, a type wheel having its type adapted to be exposed through said slotted top wall, a platen for pressing the work into 45 engagement with the type on the type wheel, a support for the platen permitting the work to be fed rearwardly over the top of the casing, and two spaced projections extending from the rear wall of the casing 50 curved upwardly to a plane above the casing top and thence downwardly and serving to support the work to prevent blurring of the printed matter.

15. In combination with a check printing machine of the type having a slotted work support, a platen for pressing the work through the slot, and a bridge supporting the platen and supported at opposite sides of the work support, single-check 55 work-gages each formed of a U-shaped portion, one arm of which is adjustably secured to the upper face of the bridge and the other arm of which extends under the bridge and has a stop portion coöoperating 60 with the work support.

16. In a check printing machine, a type cylinder having lines of type thereon any one of which is movable to a printing position, a centering device acting to center each line as it is brought to printing position, 70 and a second centering device acting to center certain lines which are separated from each other by other lines on the printing cylinder, either of said centering devices being movable out of coöperation with the printing cylinder so that the other may remain in action.

17. In a check printing machine, a type cylinder having lines of type thereon, two notched wheels turning with said cylinder, 80 one of said wheels having notches corresponding in number with the line of type on the type cylinder, and the other having notches corresponding in number to certain lines of type on the type cylinder which are separated from each other by an equal number of lines of type, and two spring pressed devices for coöoperating with the notched wheels to center the printing cylinder, each of said devices being adapted to be 85 moved out of coöperation with its notched wheel.

18. In a check printing machine, a type cylinder having lines of type thereon any one of which is movable to a printing position, and means for centering each line as it is brought to printing position or for centering only certain lines which are separated from each other by other lines on the printing member.

19. In a check printing machine, a type cylinder having lines of type thereon, any one of which is movable to a printing position, two centering wheels movable with said cylinder one having notches for each line of type on the cylinder and the other having notches only for certain lines which are separated from each other by other lines, and means for coöoperating with either of said centering wheels to center the lines 105 of type at printing point.

20. In a check printing machine, a type cylinder having lines of type thereon, any one of which is movable to a printing position, two centering wheels movable with 110 said cylinder one having notches for each line of type on the cylinder and the other having notches only for certain lines which are separated from each other by other lines, and means for coöoperating with either of said centering wheels to center the lines of type at printing point, said means comprising a centering plunger shiftable to engage either of said centering wheels.

21. A centering device comprising a 125 spring pressed plunger having a ball loosely mounted thereon to be carried therewith in both directions.

22. A centering device comprising a rotary member, a spring pressed tubular 130

plunger eccentrically mounted therein, and a ball carried by said tube.

23. In a check printing machine, a type cylinder having lines of type thereon, any one of which is movable to a printing position, two centering wheels movable with said cylinder one having notches for each line of type on the cylinder and the other having notches only for certain lines which are separated from each other by other lines, and means for coöperating with either of said centering wheels to center the lines of type at printing point, comprising a spring pressed plunger, and a pivoted carrier on which said plunger is carried to engage either of said centering wheels.

24. In a check printing machine, a casing having a slotted top wall serving as a work support, a type member having its type adapted to be exposed through said slotted top wall, a platen for pressing the work into engagement with the type on the type member, a support for the platen permitting

the work to be fed rearwardly over the top wall of the casing, and spaced devices in rear of said slot for engaging the under side of the work on opposite sides of the printed matter to lift the work off the top wall as the work is moved rearwardly.

25. In a printing machine, a casing, two printing wheels within the casing rotatable about a common axis, one of said wheels having a shaft rigidly secured thereto to turn therewith and extending through a side wall of the casing, a dial and a hand wheel secured to said shaft, a second hand wheel mounted at the opposite side of the casing and connected to the other printing wheel to turn the latter, and a second dial having a sleeve surrounding the shaft of the first named dial so that the two dials lie side by side, said sleeve extending into the casing and being connected to the second hand wheel to be turned by the latter.

HENRY J. PLANT.
